DOMICAL STRUCTURE

Helen Bryan English, Los Angeles, Calif.
(16725 Knollwood Drive, Granada Hills, Calif. 91344)

Filed Jan. 31, 1968, Ser. No. 10,379

Term of patent 14 years

(Cl. D13—1)

The ornamental design for a domical structure, substantially as shown and described.
